KNITTING MACHINE

George E. Henning, Baltimore, Md., assignor to
 Western Electric Company, Incorporated, New
 York, N. Y., a corporation of New York

Application July 10, 1946, Serial No. 682,619

10 Claims. (Cl. 66—9)

1

This invention relates to knitting machines, and more particularly to knitting machines for knitting strands into fabrics around moving cores.

In the past, there have been used knitting machines including knitting heads having needle guide cylinders provided with radial guide slots for guiding knitting needles. The knitting heads are rotated as a conductor is advanced therethrough, and the needles are reciprocated up and down in the radial guide slots and are directed radially outwardly from the cylinder. Stationary guides serve to guide strands to the knitting needles, which engage the strands one after another. As the needle guide cylinder and the needles are rotated, the strands are drawn through the guides, and the portions thereof between the guides and the needles by which they are engaged lie in planes chordal to the cylinder. Hence, these portions of the strands are not in planes transverse to the directions the hooks of the needles point when the hooks are about to engage the strands. Consequently, the hooks sometimes fail to engage the strands and thereby cause imperfections in fabric knitted by the needles. Another source of difficulty in the past has been that the hooks of the knitting needles are drawn into the guide slots and draw the strands into the guide slots, whereby the strands are sometimes abraded by the edges of the guide slots.

An object of the invention is to provide new and improved knitting machines.

A further object of the invention is to provide new and improved knitting machines for knitting strands into fabrics on moving cores without imperfections in the fabric and without abrasion of the strands during the knitting operations.

A knitting machine illustrative of the invention includes a knitting head, which is provided with a plurality of knitting needles having forwardly directed hooks and a needle guide cylinder having a plurality of slots which extend laterally along portions of chords of the guide cylinder. The needles are mounted for reciprocation in the slots, and have hooks which move in and out of the upper ends of the slots. The upper ends of the slots are enlarged so that strands drawn into the upper ends of the slots by the hooks are not abraded by the edges of the slots. The knitting head is rotated in a predetermined direction and strands are guided by stationary guides to the knitting head. The guide slots in the guide cylinder are all laterally

2

directed somewhat in the direction of rotation of the guide cylinder so that the hooks of the needles are directed substantially transversely to the direction in which the strands are drawn from the stationary guides. Hence, there is a more effective hooking action of the hooks upon the strands than there is in knitting machines having hooks directed more parallel to the strands.

10 A knitting machine forming a further embodiment of the invention includes a knitting head provided with knitting needles and a needle guide cylinder having guide slots formed therein. The needle guide cylinder is relieved at the upper portion thereof so that the hooks of the knitting needles are not drawn into the slots. Hence, loops of strands formed by the knitting needles are not drawn into the slots in the guide cylinder, and abrasion of the strands forming the loops is prevented.

A complete understanding of the invention may be obtained from the following detailed description of knitting machines forming specific embodiments thereof, when read in conjunction with the appended drawings, in which:

Fig. 1 is a fragmentary, front elevation of a knitting machine forming one embodiment of the invention;

Fig. 2 is an enlarged, fragmentary, vertical view of the knitting machine shown in Fig. 1 with parts thereof shown in section;

Fig. 3 is an enlarged, sectional view taken along line 3—3 of Fig. 2;

Fig. 4 is an enlarged, fragmentary elevation of a portion of the knitting machine shown in Fig. 1;

Fig. 5 is an enlarged, fragmentary, side elevation of a portion of the knitting machine shown in Fig. 1;

40 Fig. 6 is an enlarged, fragmentary elevation taken along line 6—6 of Fig. 3;

Fig. 7 is an enlarged, fragmentary, top plan view of a portion of a knitting machine forming an alternative embodiment of the invention, and

45 Fig. 8 is an enlarged, fragmentary elevation of a portion of the knitting machine shown in Fig. 7 having a portion thereof broken away.

Referring now in detail to the drawings, there is shown in Figs. 1 to 6, inclusive, a knitting machine forming one embodiment of the invention, which includes a frame 10 (Fig. 1) supporting a motor 11 having a pulley 12 thereon. The motor through the pulley 12 and a belt 13 drives gearing 14 enclosed in a gear box 15 to drive a hollow tubular shaft 17 (Fig. 2), through which

tubular shaft a capstan 18 (Fig. 1) advances a conductor 20. The knitting machine is also provided with a knitting mechanism 21 (Fig. 2), which includes a jack cylinder 25 for guiding needle jacks 26. The jack cylinder 25 is provided with a plurality of guides 27 for guiding the needle jacks, which are provided with butts 28 engaged by wobbler cams 29. The jack cylinder 25 is rotated by the hollow tubular shaft 17, and, as it rotates, the needle jacks 26 are rotated therewith and the wobbler cams 29 reciprocate the needle jacks up and down, as viewed in Fig. 2, in the guides 27.

A needle guide cylinder 30 is mounted rigidly with respect to the jack cylinder 25 and is rotated therewith. The needle guide cylinder serves to guide needles 31 to 44 (Fig. 3), inclusive, and carries them therewith. The needles have nibs 50 (Fig. 2), which fit into slots 51 formed in the needle jacks 26 and are also provided with straight shanks 52 (Fig. 5) and hooks 53. The needles have slots 54 therein at the junctures of the hooks 53 and the straight shanks 52, and pins 55 secure latches 56 pivotally to the junctures of the hooks 53 and the shanks 52. The hooks 53 are provided with straight shank portions 60, which angle in the directions the hooks point from the straight shanks 52 so that hook portions 61 of the hooks 53 project forwardly in the directions in which they are pointed more than they would if the shank portions 60 of the hooks were not directed angularly with respect to the shanks 52.

The needle guide cylinder 30 (Fig. 3) is provided with non-radial guide slots 62 for guiding the needles 31 to 44, inclusive. The upper portions of the guide slots 62 are provided with enlarged portions 63 at the upper end of the needle guide cylinder, as viewed in Fig. 4. Strands, illustrated by strands 71 and 72 (Fig. 3), are knitted by the knitting needles 31 to 44, inclusive, into a fabric 70 around the conductor 20, and are drawn from cops 73 (Fig. 1) supported by cop holders 74. The strands are drawn over intermediate guides 80 from the cops 73 to the knitting mechanism 21 by the knitting needles, and the downward movement of the conductor 20, which draws the fabric 70 therewith. The strands pass from the intermediate guides to guides, illustrated by guides 81 and 82 (Fig. 3), which are positioned above the needle guide cylinder 30, as viewed in Fig. 6, and are positioned almost directly over the outer periphery of the needle guide cylinder.

In the operation of the knitting machine described hereinabove, the jack cylinder 25 (Fig. 2) and the needle guide cylinder 30 are rotated in a counterclockwise direction, as viewed in Fig. 3. This rotation causes the needle jacks 26 to be reciprocated up and down, as viewed in Fig. 2, and the needles 31 to 44, inclusive, are reciprocated up and down and knit the strands into the fabric 70 upon the conductor. Each of the non-radial guide slots 62 is directed along equally spaced and equal length chords of the needle guide cylinder 30 and face markedly in the direction of rotation of the needle guide cylinder so that each of the hook portions 61 of the hooks 53 is directed perpendicularly to the plane in which the particular strand the hook portion is to engage when the particular needle hook is moved from its uppermost position so that the hooking action of the hooks 53 is most effective. This action is accentuated by the forwardly directed shank portions 60 of the hooks 53, which project

the hook portions 61 farther over the strands to be hooked.

The action of the knitting mechanism 21 is best illustrated in Figs. 3 and 6. The needle 31 has just been moved to its lowermost position, as viewed in Fig. 6, and the hook 53 thereof has just been drawn downwardly through a loop 91 of a strand 92 previously formed by the needle 31, and has drawn the strand 72 through the loop 91 to form a loop 93 of the strand 72. It should be noted that the loop 93 does not come in contact with the needle guide cylinder 30 because of the enlarged portion 63 of the slot 62, which provides clearance for the loop 93 even though this loop is drawn into the slot 62 by the hook 53.

As the guide cylinder 30 is rotated in a direction in which the periphery thereof travels to the right, as viewed in Fig. 6, the needle 31 is moved upwardly to slide the loop 93 downwardly thereon, and the needle 32, which is just behind the needle 31 in its rotation, is moved downwardly from a position near its uppermost position, and the outwardly and forwardly directed hook 53 of the needle has a loop 94 of a strand around the shank 52 thereof. The hook portion 61 of the hook 53 of the needle 32 is directly over a feeder portion 96 of the strand 72 as the strand 72 is drawn from the guide 82 by the needle 31. As the needle 32 is moved downwardly, the hook portion 61 thereof is moved over the feeder portion 96 of the strand 72 by the rotation of the needle guide cylinder 30 and projects substantially perpendicularly through the plane in which the feeder portion 96 lies.

The hooking action of the hook 53 of the needle 32 is positive, which would not be true if the hook portion 61 thereof were directed at a smaller angle with respect to the plane in which the feeder portion 96 of the strand 72 lies at the instant the hook portion 61 engages it. Furthermore, the portion of the strand 72 over which the hook portion 61 is moved is lower than is the portion of strand which would be engaged if the needle were directed radially with respect to the needle guide cylinder. This prevents formation of drop stitches and makes the hooking action of the needles more positive. Since the portion of strand to be engaged is lower, faulty latch action will not cause drop stitches as the latch will push the strand under the hook and will not lose the strand. Also, since the hooks 53 are bent forward from the straight shanks 52 the hook portions 61 project farther over the feeder positions of the strands during the hooking actions so that there is less chance of one of the hooks missing a feeder portion.

The knitting mechanism 21 (Fig. 2) serves to form the strands illustrated by the strands 71, 72, and 92 into the fabric 70 (Fig. 3) so as to avoid imperfections in the fabric from any of the knitting needles 31 to 44, inclusive, missing the feeder portions of the strands, illustrated by the feeder portion 96, as the needles are moved downwardly in their reciprocations. The strands are not abraded by the edges of the slots as they are knitted into the fabric, which abrasion is prevented by the clearance provided by the enlarged portions 63 of the slots 62 while the slots 62 serve to positively guide the knitting needles in their reciprocations.

A knitting mechanism 121 (Figs. 7 and 8) forming an alternative embodiment of the invention is identical with the knitting mechanism 21 except that a needle guide cylinder 130 thereof differs from the needle guide cylinder 30 of

the knitting mechanism 21. The needle guide cylinder 130 is provided with slots 162 for guiding needles 131, which are identical with the needles 31 to 44, inclusive. The slots 162 are positioned in the guide cylinder 130 identically with the positions of the slots 62 in the needle guide cylinder 30, but are provided with shallow portions 163 at the upper ends thereof, which are formed by a relieved portion 132 of the needle guide cylinder 130. Deep portions 164 of the slots 162, which are below the relieved portion 132 of the needle guide cylinder 130, effectively guide the needles 131 and the guiding actions thereof are aided by the shallow portions 163 of the slots 162. Hooks 153 of the needles 131 project forwardly sufficiently from straight shanks of these needles that when the needles are in their lowermost positions, as illustrated by the position of the needle 131 shown in Fig. 8, hook portions 161 of the hooks 153 do not enter the slots 162 at all. Hence, a loop 193 of a strand 172, which loop has just been formed from a feeder portion 196 of the strand 172, is not drawn into any portion of the slot 162 so that there is no possibility of abrasion of the loop 193 by the edges of the slot 162.

The operation of the knitting mechanism 21 is identical with the operation of the knitting mechanism 21 (Fig. 2) except that the hook portions 161 of the knitting needles 131 do not enter the slots 162 in the needle guide cylinder 130 at any time during the operation. Hence, wear of the strands knitted into the fabric by the needles is prevented.

It is believed to be obvious that the above-described embodiments of the invention may be variously modified without departing from the spirit and scope of the invention, as defined in the annexed claims.

What is claimed is:

1. In a machine for knitting strand material about a core, a rotatable needle guide cylinder having non-radial guideways formed therein, reciprocable knitting needles positioned in said guideways with the hooks of the needles directed non-radially with respect to the guide cylinder, and means for feeding the strand of material to the hook of the needle, each of said hooks being positioned to face somewhat in the direction of rotation of the cylinder and adapted to engage the strand out of contact with the guide cylinder when the needles are reciprocated in knitting the strand material into a fabric about a core.

2. In a knitting machine, the combination of a rotatable needle guide cylinder having a plurality of guide slots disposed non-radially therein, each of said guide slots being directed along equally spaced and equal length chords of the needle guide cylinder and facing somewhat in the direction of rotation of the cylinder, a plurality of hooked knitting needles mounted reciprocably in the guide slots, the portion of said slots adjacent to the hooks being enlarged circumferentially, said needles adapted to draw a loop of a strand into the enlarged portion of the slots without contacting the walls thereof, and means for reciprocating the needles in the slots.

3. In a machine for knitting strand material about a core, the combination of a rotatable needle guide cylinder having a plurality of guide slots disposed non-radially therein, each of said guide slots being directed along equally spaced and equal length chords of the needle guide cylinder and a plurality of knitting needles

mounted reciprocably in the guide slots, each of said needles having a forwardly bent hook portion facing in the direction of rotation of the cylinder adapted to positively engage said strand out of contact with the needle guide slots in the cylinder when the needles are reciprocated to knit the strand material about a core.

4. In a knitting machine, including means for supplying strands, the combination of a plurality of needles having forwardly bent hook portions, a needle guide cylinder having a plurality of slots formed therein, each of said slots serving to receive one of the needles, the portion of the needle guide cylinder including the walls of the slots adjacent to the hooks of the needles being relieved circumferentially to prevent abrasion by the needle guide cylinder of strands engaged by the hook portions of the needles, said needles adapted to draw a loop of a strand into the relieved portion of a slot without contacting the sides thereof, and means for rotating the needle guide cylinder in a predetermined direction, said slots in the needle guide cylinder being directed laterally forward in the direction of rotation.

5. In a knitting machine including means for advancing a core, a plurality of cop-holders for mounting a plurality of cops of strand, a plurality of needle jacks, means for reciprocating the 30 needle jacks, a rotatable jack cylinder for guiding the jacks, the combination of a plurality of knitting needles having hooks thereon and also being engaged by the needle jacks and reciprocable therewith, means for guiding the needles 35 in their reciprocations and for revolving the needles around the core advanced by the advancing means, and stationary means for guiding the said strands to some of the needles along predetermined paths, said needle-guiding means serving to retain the needles in positions in which the hook of each needle is directed substantially 40 perpendicularly to a plane in which lies a portion of one of the strands which the hook of that needle is intended to engage when it is moved toward that strand.

6. In a knitting machine including a plurality of cop-holders for mounting a plurality of cops of strand, a plurality of knitting needles having hooks for engaging the strands, a plurality of 50 jacks for positively engaging the knitting needles, a jack cylinder having guide portions spaced along a circle for mounting the jacks, means for advancing a core through the jack cylinder, means for rotating the jack cylinder around the core to revolve the jacks around the core, stationary means for guiding strands from the cops to substantially alternate ones of the knitting needles and means for reciprocating the jacks to reciprocate the needles, said reciprocating 55 means serving to reciprocate the jacks in such a manner that when one of the needles is near one end of its reciprocation the needles immediately adjacent thereto are at the opposite ends of their reciprocations, the combination 60 which comprises a needle guide cylinder positioned coaxially with respect to the jack cylinder and rotatable therewith for revolving the needles around the core, said needle guide cylinder being provided with a plurality of needle-orienting slots lying in planes non-radial to the guide cylinder for mounting the needles so that the hooks thereof are substantially perpendicular to strands they engage at the times the hooks engage the strands.

7. In a knitting machine including a plurality

of cop-holders for mounting a plurality of cops of strands, a plurality of knitting jacks, a knitting jack cylinder having a plurality of guideways spaced around the cylinder for receiving the knitting jacks and means for rotating the jack cylinder in a predetermined direction, the combination which comprises a needle guide cylinder carried by the jack cylinder and rotatable therewith, said needle guide cylinder being provided with a plurality of guide slots in the portion thereof near the periphery thereof, said slots extending laterally outwardly with respect to the center of the needle guide cylinder, longitudinally upwardly and laterally in the direction of rotation, and a plurality of knitting needles reciprocable by the jacks and positioned in the slots in the needle guide cylinder, said needles being provided with hooks for knitting the strands into a tubular fabric, said needle guide cylinder being provided with relieved portions to provide clearance for strands engaged by the hooks of the knitting needles.

8. In a knitting machine including means for supplying strands, a rotatable needle guide cylinder having an annular outwardly projecting flange portion, said cylinder including the flange portion having a plurality of guide slots disposed non-radially and facing somewhat in the direction of rotation of the cylinder, a plurality of knitting needles mounted in said slots, said needles having forwardly bent hook portions which always remain outside of said slots and above said annular flange portion of the cylinder, and means for reciprocating the needles in the guide slots.

9. In a knitting machine including means for supplying strands, a rotatable needle guide cylinder having a plurality of guide slots, each of said slots being disposed non-radially and faced somewhat in the direction of rotation of the cylinder, a plurality of hooked knitting needles mounted in said slots, the portion of said slots adjacent to the hooks being enlarged circumferentially, said needles adapted to draw a loop of a strand into the enlarged portion of a slot with-

out contacting the walls thereof, and means for reciprocating the needles in the slots.

10. In a knitting machine including means for supplying strands, a rotatable needle guide cylinder having an outwardly projecting flange portion, said cylinder including the flange portion having a plurality of guide slots disposed non-radially and facing somewhat in the direction of rotation of the cylinder, a plurality of knitting needles mounted in said slots, said needles adapted to draw a loop of a strand towards said flange without permitting the strand to contact the sides of said guide slots, and means for reciprocating the needles in the slots.
